US00D825024S

(12) **United States Design Patent** (10) Patent No.: **US D825,024 S**
(45) Date of Patent: ** Aug. 7, 2018

(54) **INSECT TRAP**

(71) Applicant: **RENTOKIL INITIAL 1927 PLC**,
Surrey (GB)

(72) Inventors: **Gary Wingett**, Southampton (GB);
Michael Best, Southampton (GB);
Vicky Rands, Salisbury (GB)

(**) Term: **15 Years**

(21) Appl. No.: **35/503,095**

(22) Filed: **May 22, 2017**

(80) **Hague Agreement Data**

Int. Filing Date: **May 22, 2017**

Int. Reg. No.: **DM/096166**

Int. Reg. Date: **May 22, 2017**

Int. Reg. Pub. Date: **Jun. 9, 2017**

(51) **LOC (11) Cl.** 22-06

(52) **U.S. Cl.**

USPC **D22/123**

(58) **Field of Classification Search**

USPC D22/119-124

CPC A01M 1/02; A01M 1/14; A01M 2200/012

See application file for complete search history.
